[57] CLAIM

The ornamental design for a cocktail table, or the like
substantially as shown and described.

DESCRIPTION

FIG. 1 is a view in top plan of a cocktail table or the like
showing my design;

FIG. 2 is an elevational view showing one of the two
identical sides; and

FIG. 3 is an elevational view showing one of the two
identical ends.

FIG. 1

FIG. 2

FIG. 3
